UNITED STATES PATENT OFFICE.

ESTELLE ALLISON, OF NEW YORK, N. Y.

DESIGN FOR A TOY FIGURE.

49,916.

Specification for Design.

Patented Nov. 21, 1916.

Application filed September 23, 1916. Serial No. 121,899. Term of patent 7 years.

To all whom it may concern:

Be it known that I, ESTELLE ALLISON, a citizen of the United States, and a resident of the city and county of New York, State of New York, have invented a new, original, and ornamental Design for a Toy Figure, of which the following is a specification, reference being had to the accompanying drawings, forming part thereof.

I claim:

ESTELLE ALLISON.

Witness:

H. GOODRICH.
